UNITED STATES PATENT OFFICE

HENRY MILTON GRILLS, WILLIAM O. BLAGDON, AND EDWARD J. BRISBOW, OF
TORONTO, ONTARIO, CANADA

FIRE EXTINGUISHER

Application filed January 26, 1929. Serial No. 335,240.

Our invention relates to a grenade holder, characterized by an upright member, a shelf or ledge disposed at an oblique angle to the vertical plane of the upright member and preferably integral with or infusibly connected to it, at or near its lower end, upon which the grenade may be seated, and a retaining member fusibly connected to the upright member for overlying and embracing 10 or partly embracing the grenade and preventing its displacement from the shelf.

For an understanding of the invention, reference is to be had to the following description and to the accompanying drawings in 15 which:

Fig. 1 is a sectional elevation of the fire extinguisher showing in full lines the several parts of the grenade holder and in dotted lines a grenade seated on the shelf and retained in position by a segmental strap fusibly connected to the upright member.

Fig. 2 is a front elevation of the construction shown in Fig. 1.

Fig. 3 is a sectional elevation of a modification of the grenade holder shown in Figs. 1 and 2.

Fig. 4 is a front elevation of the construction shown in Fig. 3, and

Fig. 5 is a cross section on the line 5—5, 30 Fig. 1.

Like characters of reference refer to like parts throughout the specification and drawings.

The grenade holder comprises an upright member 1 which may conveniently take the form of a flat plate of a height corresponding to that of the grenade 2; the upper part 3 of the upright member being preferably shaped to conform to the grenade and provided with a lug 4, extending upwardly from its extremity and formed with an aperture 5 through which a hook or other hanger may be entered for attaching the holder to a supporting structure.

Integral with or connected to the upright member 2, at or, near its lower end, and disposed at an oblique angle to its vertical plane, is a shelf or ledge 6 which in the form shown in the drawings has a downward-forward inclination, and in the bottom of the shelf or

ledge is a recess 7. This recess in the construction shown in Fig. 2 takes the form of an aperture extending through the shelf or ledge and in the construction shown in Fig. 1 takes the form of a cup shaped socket, the wall 8 of which is below the shelf or ledge and the axis of which has a downward-rearward inclination from the under side of the shelf. When the parts are assembled the grenade is seated on the shelf or ledge with its neck or base entered through the aperture 7 to prevent its lateral displacement. The downward-forward inclination of the shelf or ledge causes the grenade to slightly overbalance outwardly from the holder for ensuring its positive dislodgment when the retaining member 9 embracing or engaging the upper part of the grenade separates from the upright member. The retaining member 9 shown in Figs. 1 and 3 consists of a segmental band one end of which is free and the other end of which is secured to the upper part of the upright member by a fusible rivet 10, capable of melting at a relatively low temperature.

The retaining member 9 overlies and partly embraces the dome of the grenade and, in conjunction with the shelf or ledge, maintains it in its set position in the holder until the fusible rivet melts. When that occurs the retaining member separates from the upright member, and the grenade, owing to its overbalanced condition falls from the holder and breaks for the liberation of its fire extinguishing contents.

The retaining member, the upright member, and the shelf or ledge are made of metal of sufficient tensile strength and rigidity to sustain the weight of the grenade and its contents under conditions of reasonable use and when the grenade is assembled with the holder its weight is borne principally by the upright member and shelf or ledge, the only weight or strain imposed on the retaining member and fusible rivet being that resulting from the slightly overbalanced condition of the grenade.

The free end 11 of the retaining member is of a relatively considerable width to provide sufficient contact surface with the

grenade for preventing its inadvertent movement in a forward direction and the other end or fixed end 12 is of a width approximating the width of the upright member.

5. At the extremity of the fixed end 12 of the retaining member is a narrow tip 13, loosely entered through a hole 14 in the upper part of the upright member which in conjunction with the fusible rivet prevents the inadvertent movement of the retaining member in a lateral direction.

At the sides of the upright member, interjacent the shelf or ledge and the retaining member, are lateral enlargements 15 having forwardly projecting lugs 16 for embracing the grenade and preventing its lateral movement in the holder.

Having thus fully described our invention what we claim as new and desire to secure by Letters Patent is:

1. In a fire extinguisher, a grenade holder comprising an upright member, a shelf connected to the upright member and disposed at an oblique angle to its vertical plane upon which the grenade may be releasably seated and a retaining member fusibly connected to the upright member for overlying and embracing or partly embracing the grenade.

2. In a fire extinguisher, a grenade holder comprising an upright member, a shelf connected to the upright member and disposed at an angle to its vertical plane, said shelf having a downward-forward inclination and a retaining member fusibly connected to the upright member for overlying and embracing or partly embracing the grenade.

3. In a fire extinguisher, a grenade holder comprising an upright member, the upper part of which is shaped to conform to the grenade, a shelf connected to the upright member near its lower end and disposed at an oblique angle to its vertical plane, a retaining member fusibly connected to the upright member for overlying and embracing or partly embracing the grenade, and an apertured recess in the shelf for the base of the grenade.

4. In a fire extinguisher, a grenade holder comprising an upright member, a shelf, connected to the upright member and disposed at an oblique angle to its vertical plane, on which the grenade may be seated, said shelf having an apertured recess for the base of the grenade, and a retaining member fusibly connected to the upright member for overlying and embracing or partly embracing the grenade.

5. A fire extinguisher, as claimed in claim 1 in which forwardly projecting lugs are provided at the sides of the upright member for embracing the grenade and preventing its lateral movement in the holder.

6. In a fire extinguisher, a grenade holder comprising an upright member the upper part of which is shaped to conform to the

grenade, a shelf connected to the upright member near its lower end and disposed at an oblique angle to its vertical plane, forwardly projecting lugs at the sides of the upright member for embracing the grenade and preventing its lateral movement in the holder, a retaining member fusibly connected to the upright member for overlying and embracing or partly embracing the grenade, and a socket in the shelf for the base of the grenade.

7. A fire extinguisher, as claimed in claim 6 in which the wall of the socket is located below the underside of the shelf.

8. A fire extinguisher, as claimed in claim 6 in which said shelf has a downward-forward inclination from the upright member and the socket has a downward-rearward inclination from the underside of the shelf.

Dated at the city of Toronto, in the county of York, and Province of Ontario, Dominion of Canada, this fourteenth day of January, 1929.
